UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

RADIO SERVICE METERING SYSTEM.

Original application filed January 6, 1925, Serial No. 913. Divided and this application filed August 1, 1925. Serial No. 47,545.

The present application is a division of my copending application Serial No. 913, filed January 6, 1925.

My invention relates to systems of radio broadcast distribution, and has for its objects in particular to produce a subscriber's instrument and to relate the same to central office apparatus in such manner that programs may be originated, relayed and distributed over a wide area, in a systematic and orderly manner; so that ultimate receiving stations may be controlled and operated as subscribers' stations and the programs distributed may be confined to said subscribers' stations and not be available for outside receiving stations not forming a part of the system; so that subscribers may select different programs or different items from different programs as time of rendition proceeds; so that subscribers may obtain any item produced and distributed from any part of the system to any other part of the system and within the range of their selective apparatus; so that while the subscribers may get the full benefit of amplification and the use of vacuum tubes in receiving and amplifying, yet their stations will be tubeless, that is to say, all the tubes pertaining to subscriber's receiving apparatus shall be located at central points, which may be also the final distributing points through which the programs or signals are given to the subscribers; so that all reception by the subscriber of programs or program items selected by him, shall be differentially metered according to the value fixed upon them by the broadcasting authorities, and automatically recorded at the rates so determined; so that a subscriber may have nothing at his station but standard telephone apparatus, connected and operating in conjunction with telephone line circuits, but capable of operating a loud speaker when desired; and finally so that the entire control, supervision, metering, current supply, installation and maintenance of subscribers' instruments will be from organized central stations provided with expert operators.

I attain these and other objects which will sufficiently appear hereinafter by connecting all the subscribers' stations in groups to localized central offices or exchanges, supplying such exchanges with broadcast matter over trunks, from a relay broadcast service

station having receiving instruments which may be of any suitable type, such as those described in my prior copending application, Serial No. 746,357, filed October 28, 1924; providing line circuits entering a central station with vacuum tubes, one for each line, constituting terminals of the lines for radio distribution; and finally connecting these distributing tubes, which may be audio frequency amplifiers, to the trunks leading from the appropriate receiving devices at the broadcast service station, and employing these connections as well as the conditions brought about by the subscribers, to operate meters, and to enable the central office operators to variously control, supervise, etc.

This invention is applicable to manual, automatic or so-called semi-automatic or automanual telephone systems, as will sufficiently appear hereinafter. The main underlying principle involved is that of distributing from a broadcast service station through a central station to a plurality of subscribers' lines by means of individual line tubes or valves, so that each line may have its own self contained receiving unit, needing only excitation by the central office relay transmitter, combined with means for metering the service rendered the subscriber.

The method I have found most satisfactory in practice is to include one stage of audio amplification in each relay set or transmitter, the line tubes constituting a second stage. Current carrying capacity and power of the line tubes may be varied within wide limits, affording any amount of energy for transmission and any class of service that is desired. If the exciting circuits connected to any one bus at one time are too many, the busses may be banked by means of tubes in parallel as well understood in the art. In this case, each relay transmitter at the broadcast service station would preferably have a detector tube connected through a transformer to a plurality of audio amplifier tubes in parallel, constituting a multiplied first stage, the plate circuits of which would be connected to the bus through a suitable transformer.

Regulation of the current flow from the B or plate battery through each bus during program transmission may be obtained by means known in the art and usually manipulated by an operator at a transmitting station.

Some modifications can be made in the arrangement and many modifications in the detail of circuit and design, but I feel the principle as stated to be novel in its application and original with myself, and I shall claim the same accordingly.

My invention is illustrated in the accompanying drawings, in which:

Figs. 1 and 2 indicate, diagrammatically, the telephone exchange portion, and broadcast distributing portion, respectively, of my combined telephone exchange and broadcast distributing system.

Fig. 3 is a diagram of the broadcast service station.

Fig. 4 is a modification of the circuit arrangement of Fig. 2.

Fig. 5 is a modified form of the switch arrangement of Fig. 4.

Fig. 6 is a diagram showing the operative relation and connections between different stations in a general system of broadcast distribution embodying the invention.

Fig. 7 is a diagram of a trunking arrangement for extending a subscriber's line circuit outside the local central station.

Fig. 8 is a schematic diagram showing the general arrangement for distribution of a broadcast program through an amplifier circuit common to a plurality of lines and second stage amplifier tubes and circuits individual to the subscriber's line.

Referring to the drawings in detail, and first to Fig. 1, this shows the essential circuits of an ordinary telephone exchange system in which A' is a subscriber's station connected by line wires 69-70 to the central station C where they terminate on multiple jacks J. Similarly, the multiple jacks J' form the line terminals of another substation not shown. These jacks are arranged to be interconnected through the usual answering and calling plugs P-P' forming the terminals of the usual common battery cord circuit shown. The central office terminals of each line are provided with the usual line relay L¹, line lamp L² and cut-off relay L³. Where service is to be metered a recording meter M is also individually associated with the line. Thus, the circuit arrangement here shown is that of the standard multiple switchboard, common battery, telephone exchange system, and as such as well understood in the art further detailed description thereof will be here deferred and brought out later in the description of operation. In addition to the usual line terminal multiples 1, 2 and 3, representing multiples of the tip, sleeve and test or cut-off circuits, respectively, I provide a fourth conductor 4 leading from a contact on the line relay along with the multiple conductors 1, 2 and 3 to the broadcast distributing system diagrammed in Fig. 2.

Fig. 2 shows the broadcast distributing

system of which the portion to the left of the dotted line is situated at the central office and connected with the subscriber's telephone line terminal apparatus of the telephone central C (Fig. 1) through conductors 1, 2, 3 and 4, while the portion to the right of the dotted line in Fig. 2 is situated at the subscriber's telephone substation apparatus A' (Fig. 1) through the multiple conductors 5 and 6. In Fig. 2 the subscriber's line multiples 1-2 terminate in contacts 7-8 of an automatic selector switch 800. This switch is of a type well understood in the automatic telephone art in which movable contacts or wipers such as 7 and 8 are carried on a shaft 10 biased in a given normal position by a spring or other suitable means not shown and arranged to be stepped around by a stepping magnet 11 through a stepping pawl 12 and a ratchet 13. Also, as is usual with such switches, it is provided with a dog 14, arranged to be thrown out of engagement with the ratchet 13 and to throw the stepping pawl 12 out of engagement when the dog is stepped by the actuation of the release magnet 15, the energization of the release magnet 15 effecting the tripping of the dog 14 through an extension 16 on its armature 17 pivoted at 18. To hold up the armature extension 16 until the switch has released, a trip detent 19 is provided which is pivoted at 20 and arranged to be held normally out of engagement with the hook 21 on the armature 17 by a cam 22 on the switch shaft which permits the detent 19 to move into operative relation with the hook 21 whenever the switch is in off-normal position. Mounted on the switch shaft 10 are other pairs of wipers 23-24, 25-26, and 27-28. The switch 9 is provided with a contact bank containing rows of contacts 30, 31, 32 and 33 arranged to be engaged by the switch wipers 7-8, 23-24, etc., successively in the direction indicated by the adjacent arrow, it being understood that while the drawing, which is purely diagrammatic shows the contacts arranged in a straight line they are in practice arranged in a circle concentric with the switch shaft so as to permit the switch arms to sweep across them in the rotation of the shaft. While only three vertical rows of contacts are here shown it is to be understood that they may be more or less in number and that in any case the first few vertical rows of contacts are left blank or disconnected, for example, in the present case the first five, leaving the sixth vertical row of contacts the first ones that are connected with the operating circuits so that the switch must make five stops before effecting any circuit connections, after which the wipers will be moved successively to the sixth, seventh and eighth vertical rows. The purpose of providing this lost motion or blank steps will be made clear in the description of

operation. The switch wipers 23-24 connect with the adjacent terminals of the winding 34-35 of a repeating coil 36, the remote terminals of which windings connect to the 5 plate and filament of the audion tube 37. The switch wipers 25-26 connect to the grid and filament of the tube 37, while the wipers 26 and 28 form the terminus of the filament of the tube 37. The wiper 27 is connected 10 to the multiple test wire 3, leading into Fig. 1. The horizontal row of contacts 30 are connected as multiple pairs, the upper and lower members being connected respectively to the remote terminals of the coils 38 at 15 39 of the repeating coil 36 through the conductors 40 and 41, the conductor 41 connecting with the coil 39 through a sleeve or line supply relay 42, shunting resistance 43 and conductor 44. The adjacent terminals of 20 the coils 38 and 39 are connected to the plus and minus side of the exchange common battery B through conductors 45 and 46, and bus conductors 47 and 49, respectively. In 25 the horizontal row of contacts 31, the sixth, seventh and eighth pairs are connected individually to the batteries B⁶, B⁷, and B⁸ respectively. In the horizontal row of contacts 32, the sixth, seventh and eighth pairs are connected, respectively, to the different 30 program distributing buses 66, 67 and 68, the lower contacts of the sixth, seventh and eighth pairs being connected respectively to the bus wires of filament batteries F⁶, F⁷, and F⁸ respectively. In the horizontal row 35 of contacts 33 the upper members of each pair are connected in multiple to the conductor 49 which supplies battery current for the test by its connection through repeat relay 50, conductor 46 and bus 48 to the central 40 office common battery B. The lower contact members of the horizontal row 33 are connected individually to the upper bus wires of the different filament batteries F⁶, F⁷, and F⁸. Thus the batteries B⁶, B⁷, and B⁸, 45 the program busses 66, 67, and 68, and the filament batteries F⁶, F⁷, and F⁸ are associated individually with the sixth, seventh and eighth vertical rows of contacts, respectively. The stepping magnet 11 and release 50 magnet 15 have their windings connected in multiple, one side to ground and the other side through conductor 51 to an impulse wire 4 leading into Fig. 1 where it terminates in a front or normally open contact 52 of the line relay L', which contact is engaged by the armature 53 connected through wire 54 to the exchange common battery B. The conductor 51 is also connected in multiple to a normally open contact 55 engaged 55 by the armature 56 of the relay 50, the armature 56 being connected by way of conductors 46 and 48 to the exchange common battery B. The repeat relay 50 is controlled by the sleeve relay 42 through the armature 57 which is arranged, as shown to close a 60 shunt around the winding of the relay 50 by way of resistance 58. The subscriber's broadcast receiving set A² is similar in all respects to the usual booster coil, common battery telephone receiving set, except that the switchhook is replaced by a spring jack J² arranged, upon the insertion of a plug, to close the line circuit through the line multiples 5-6, winding 60 of the booster coil 61, transmitter 62 and automatic dial 63, 65 while connecting the subscriber's broadcast, telephone receiver 64 in series with the coil 65 and telephone condenser 266. The program busses 66, 67 and 68 are supplied with broadcast matter from the broadcast service 70 station Fig. 3, over trunk wires T⁶, T⁷ and T⁸, respectively which form the output terminals of program transmitting devices P⁶, P⁷, and P⁸, preferably radio receivers of a type adapted to receive radio broadcast and amplify and relay the same at audio frequency, the amplification being effected in any suitable way such as by detection and audio amplification or a combination of 75 radio amplification, detection and audio amplification, the audio amplification being preferably limited to one stage so as to allow a second stage of amplification to be made between the busses and the ultimate receiver. In this case the ultimate receiver is 80 the subscriber's broadcast receiver 64 and the second stage of audio amplification is effected through the audion tube 37 individual to 85 each line. In the operation of the arrangement shown 100 in Figs. 1, 2 and 3, the subscriber at station A' operatively connects his broadcast receiving or extension set A² to the line by inserting the receiver plug P² in the jack J² which connects his receiver 64 the booster 105 coil winding 65 and condenser 266 in series, and closes a path for direct current between the multiples 5 and 6 through coil 60, lower spring of jack J², transmitter 62, and automatic dial 63. This energizes the subscriber's 110 line relay at the central office in the usual manner by current from the central office common battery B, which energizing circuit may be traced from the grounded side of central office common battery B, conductor 115 68, right hand winding of line relay L', line conductor 69, to subscriber's substation A', line multiple 5, to subscriber's broadcast receiving set A² (Fig. 2), coil 60, transmitter 120 62, contacts of dial 63, conductor 6, 70, left hand winding of line relay L', and back to the battery B. Energization of the line relay 125 energizes the line lamp L² by closure of a local circuit which may be traced from the battery B through elements 54, L², 71, 68 and back to battery B. This causes the line lamp L² at the telephone operator's switchboard to glow, but only for a moment as the subscriber wanting broadcast service will immediately operate his dial to break and 130

make his line circuit a certain number of times according to the particular program he desires which breaks and makes will cause his line lamp to flicker instead of glowing steadily and so indicate to the telephone operator that the subscriber is not calling for a telephone connection but is automatically setting up his connection for broadcast reception. As the dial 63 is of the well known type used in automatic telephony and well understood in the art, it will not be necessary to describe the same here in detail and it suffices to say that it operates automatically to effect one or a series of breaks of brief duration in the line circuit according to the setting of the dial each time it is set and released. The first closure of the line and energization of the line relay L' completes an energizing circuit for the stepping magnet 11 (Fig. 2) which may be traced from the free side of the common battery B through circuit elements 54, 53, 52, 4, (into Fig. 2), 51 to stepping magnet 11 and release magnet 15 in multiple and thence through ground back to the grounded side of battery B. It is to be noted here that the release magnet 15 is made sluggish in its action so that it will not respond to the energizing current until after a lapse of time much longer than the interval between the breaks and makes of the subscriber's dial 63 so that when the subscriber first closes his circuit, as just described, the stepping magnet 11 will first operate to step the switch 9 around one step releasing the detent 19 after which, the time period of the release magnet 15 having lapsed, this magnet will actuate its armature to move the hook 21 up into engagement with the detent 19 and the extension 16 into engagement with the dog 14 which disengages the dog from the ratchet 13 and also throws the pawl 12 out of engagement with the ratchet, thus causing the switch to release and return to normal position whereupon the cam 22 will throw the detent 19 out of engagement with the hook 21 and leave the armature 17 free to return to normal position when the magnets become deenergized. In the case of a call for telephone connection this deenergization of the magnets would occur when the telephone operator, in answering, inserts the plug P' in the jack J' which would operate the line cut-off relay L^3 in the usual manner causing the line relay L' to retract its armature 53 and open the circuit of the stepping and release magnets 11 and 15. To prevent the subscriber's broadcast selector switch 9 from being stepped around and connecting broadcast matter on to his line due to one or more accidental breaks in his line circuit while the subscriber is waiting for telephone operator service, the selector switch 9 is provided with several blank contacts preceding those representing the different broadcast programs. In the present illustration the first five contacts are left blank, the series of active contacts beginning with those of the sixth vertical row, as indicated in Fig. 2, where the blank contacts are not shown, it being understood that the switch must make five steps before its wipers engage the first set of active contacts. Thus if the subscriber, while waiting for an operator should accidentally, momentarily open his line or impatiently operate his switch-hook a few times, the connector switch would simply step around over a few of the blank contacts and release as before described when the operator plugged in with her answering plug. Returning now to the subscriber's selection of a desired broadcast program, the subscriber, shortly after the initial closure of his line effected by his insertion of the plug P^2 in the jack J^2 , and before the line lamp has been energized sufficiently long to indicate a telephone call to the operator, sets his dial to a number corresponding to the number of the broadcast program he wishes to receive, which in the present case would be some number above five, and permits the same to release producing a number of breaks corresponding to the setting of the dial. Assuming the setting to be eight, the dial upon release will cause the line circuit to be momentarily opened eight times. The first five breaks in the line circuit will cause the armature 53 of the line relay to open and close its connection with the contact 52 five times, thus stepping the selector switch around to the fifth contact, the period of closure of the contacts 52—53 being sufficiently brief to prevent actuation of the release magnet 15. Upon the sixth momentary break and subsequent make of the line circuit, the switch 9 will step on to the sixth or first vertical row of active contacts whereupon the line cut-off relay L^3 will be energized and the control of the stepping magnet 11 transferred from the line relay to the sleeve relay 42 of the switch circuit. The energizing circuit of the cut-off relay L^3 may be traced from the common battery B (top of Fig. 2), bus wire 48, conductor 46, winding of repeat relay 50, conductor 49, upper member of the sixth contact of horizontal row 33, switch wiper 27, conductor 3, into Fig. 1, line cut-off relay L^3 , conductor 68 to grounded side of the common battery B. Energization of repeat relay 50 causes its armature 56 to engage the contact 55 thus maintaining the stepping magnet 11 energized by current from battery B through circuit elements 48, 46, 68, 55, 51, 11, to ground and back to battery B, while the energization of the cut-off relay L^3 (Fig. 1) disconnects the line relay L' in the usual manner which becoming deenergized releases its armatures 71—53, extinguishing the line lamp and opening the circuit through contacts 70 75 80 85 90 95 100 105 110 115 120 125 130

ductor 4. Simultaneously with the energization of the cut-off relay L^3 and repeating relay 50, the sleeve relay 42 is energized by current from the common battery B through the circuit elements 48, 46, 39, 42, 41, lower member of the sixth contact in the horizontal row 30, switch wiper 8, line multiple 2 into Fig. 1, line wire 70, multiple wire 6, into Fig. 1, through circuit elements 63, 62, 60, 5 into Fig. 2, 69, 1, into Fig. 2, 7, 40, 38, 45, 47, and back to the grounded side of the common battery B. Energization of sleeve relay 42 causes its armature 57 to be attracted and complete a shunt around the winding of repeat relay 50 by way of circuit elements 58, and 57, which shunt causes the relay 50 to become deenergized and retract its armature 56 opening the circuit of the stepping magnet 11 and causing it to return to normal ready for the next step. The next or seventh momentary break in the subscriber's line circuit, which follows immediately, effects a momentary release of the armature 57 of sleeve relay 42 which causes a momentary energization of the repeat relay 50 which in turn effects a momentary closure of contact 55 and a momentary energization of the stepping magnet 11 to step the switch wipers around to the seventh vertical row of contacts. The energizing circuit of the stepping magnet may be traced from the common battery B through circuit elements 48, 46, 56, 55, 51, and 11 back to the grounded side of battery B. Similarly, the next or eighth momentary break in the line causes the stepping magnet 11 to be again momentarily energized and step the switch wipers around into engagement with the eighth vertical row of contacts.

40 After the eighth momentary break in the line circuit the subscriber's dial 63 comes to rest and maintains the line circuit closed. The line now being closed, the sleeve relay 42 is maintained energized which maintains the repeating relay 50 deenergized by virtue of the closure of the shunt around its winding which in turn maintains the circuit of the stepping and release magnets 11 and 15 open at the contact 55. The switch wipers thus come to rest on the eighth vertical row of contacts, maintaining the input terminals of the subscriber's line tube 37 in operative connection with the bus wires 68 of the program transmitter P^8 (Fig. 3) through switch wipers 25—26 and the eighth pair of contacts in the horizontal row 32. Current is supplied to the output or plate circuit of the tube 37 from battery B^8 , individual to the program transmitter P^8 , over circuit elements 72, 29, 34, plate of tube 37, filament of tube 37, 75, 36, 24, 78, back to battery B^8 . As the coil 36 is a repeating coil of the well known type having the four windings 34, 35, 38, 39 on a common magnetic core the output or plate circuit of the tube 37 is coupled to the subscriber's line through the coils 38—39 which are included in series in the subscriber's line circuit as hereinbefore traced. The filament circuit of the subscriber's audion tube 37 may be traced from filament battery F^8 , individual to the program transmitter P^8 , over the circuit elements 79, lower member of bus wire 68, 26, filament of audion tube 37, filament rheostat 80, 28, 82, back to battery F^8 . As the winding 60 of the booster coil 61 at the subscriber's broadcast receiving set A^2 is included in series in the line, the broadcast matter coming therover is repeated in the winding 65 which reproduces the signal in the subscriber's receiver 64 over a circuit which may be traced from 65, through circuit elements 268, 63, 62, and through the receiver 64 back to winding 65 by way of the plug and jack connection P^2-J^2 . As the sleeve relay 42 is held energized during the subscriber's use of his line for receiving broadcast, should a telephone operator test one of his multiple jacks in the usual manner before establishing a connection therethrough to his line, instead of the ordinary busy test of a click in the ear, she will receive a special tone test which will indicate that the line is not busy for telephone use but is being used for the reception of broadcast so that if the call is an emergency one the operator may plug in regardless of the busy condition. Thus a special tone test is effected by the usual tone test apparatus indicated in Fig. 2 as consisting of the inductance 87 connected in series with a circuit breaker 88 and inductively related to the coil 58 in series in the test circuit. The energizing circuit of the coil 87 may be traced from the common battery B through the circuit elements 48, 46, 87, 88, back through ground to the battery B.

When the subscriber wishes to discontinue the broadcast reception he withdraws the plug P^2 which opens the line circuit at the jack contact 89. This deprives the sleeve relay 42 of current whereupon its armature 57 is retracted removing the shunt from the repeating relay 50 which thereupon becomes energized and closes the circuit of both the stepping magnet and the relay magnet through connection of the armature 56 with contact 55. This circuit may be traced from battery B through the circuit elements 48, 46, 56, 55, 51, 11, and 15 in multiple to ground and back to the battery B. After the brief lapse of time required for the operation of the release magnet 15 this magnet attracts its armature which brings the extension 16 into engagement with the dog 14 to trip the same which in turn trips the pawl 12 allowing the switch to return to normal, hook 21 engaging the detent 19 which holds the armature 17 in its actuated position during the restoring movement of the switch.

and until the switch reaches the normal position whereupon the cam 22 operates to disengage the detent 19 from the hook 21 and permit all parts of the switch to return to the normal position shown. When the switch in restoring moves its wipers off the sixth vertical row of contacts the circuit repeat relay 50 is broken at the wiper 27, and the repeat relay 50 deenergizing opens the circuit of the magnets 11 and 15 at the contact 55. This puts all the circuits and apparatus in the normal condition shown in Figs. 1 and 2.

For metering the subscriber's use of the radio broadcast service on a basis of time use, a meter controlling actuator 90 (Fig. 2) is arranged to control the subscriber's telephone meter M (Fig. 1) through the operative connection of the switch circuits of Fig. 2 with the subscriber's central office line terminal circuits. This control circuit may be traced from the meter generator 91 (Fig. 2) through commutator 90, switch 92, bus wire 93, switch 94, wire 49, the upper member of one of the contacts in the horizontal row 33, wiper 27, test wire 3, into Fig. 1, wire 95, high voltage winding 96, of the meter M, to ground and back to the grounded side of the meter generator 91 (Fig. 2). When the meter armature 97 is retracted a sufficient distance to close the contact 98 the low voltage winding 99 of the meter M is closed thus aiding in the further attraction of the armature and the actuation of the meter as well understood in the art, which actuation will be repeated at intervals according to the intervals of the closing and opening of the circuit meter commutator 90. These periodic registrations of the meter during use of the broadcast apparatus will of course be added to those produced by the actuation of the usual, telephone operator's metering key 100, so that the subscriber's use of the broadcast service is charged in the same units as that of the telephone use and the amount of service represented by a unit charge varied according to the speed of operation of the commutator 90. Where the service to some of the lines is to be given free the switch 94 individual to the line is opened and where the service is to be given free to all or a group of lines the switch 92 is opened to disconnect the commutator from the bus 93 common to all or a group as the case may be.

To afford communication between the broadcast service station and a subscriber's station, the broadcast service station is provided with telephone lines 230 and 231 (Fig. 3), each terminating at the service station in the usual telephone set, as represented at 232 and 233, and at the telephone central station in suitable line terminal apparatus such as the jacks J' and 235. Also at the broadcast service station, the lines 230 and

231 are provided with multiples 238 and 239 terminating in jacks 240 and 241 to enable any one of the lines to be connected with one of the transmitters such as P⁸ through a modulator M⁸ and plug connection 242. Thus the radio service operator can reach the subscriber over two paths, the subscriber can talk to the operator while listening to the broadcast, and finally the radio operator can connect the subscriber telephonically to the radio transmitter to broadcast the conversation. This combination gives in effect a complete communicating circuit made up of outgoing wave radiation and incoming or return wire communication, the latter serving to localize and fix the former. This use of the system is of value in certain classes of advertising and sales work as well as entertainment. To enable original matter or local announcements to be sent out from the broadcast service station, a microphone circuit 242 is provided which terminates in a jack 243 for connection with any one of the modulators of the transmitters P⁸, P¹, or P⁸.

Referring now to Fig. 4, this is similar to Fig. 2, just described, except that the line multiples 1-2 are permanently connected to the outside terminals of the coils 38 and 39 and the battery connection to the inside terminals of these coils controlled through the upper pair of wipers 7-8 of the switch 9, and the horizontal row 30 of the switch bank contacts. Another difference is that the repeat relay is omitted and the stepping of the switch, after connection with the active contacts, controlled through a back or normally closed contact of the sleeve relay 42 connected to battery through an off normal switch 101 controlled by a cam 102 on the switch shaft 10 arranged to maintain the off normal switch closed only during engagement of the switch wipers with one of the sets of active contacts that is, from the six vertical row on. As this is a modification of the switching circuit illustrated in Fig. 2 and intended to operate in place thereof, it is to be read in connection with Fig. 1. The conductors 1, 2, 3, 4, 5 and 6 of Fig. 4 tie on to the similarly numbered conductors of Fig. 1. In the operation of this circuit arrangement when the subscriber operates the dial 63 at his broadcast receiving set A², to effect the eighth successive momentary breaks in his line circuit, the first six cause the line relay to close the contact 52-53 six times which in turn effects six successive energizations and deenergizations of the stepping magnet 11, the successive impulses being as before described, of too brief duration to cause actuation of the release magnet 15. The energizing circuit of stepping magnet 11 may be traced from battery B (Fig. 1) through circuit elements 53, 52, 4, into Fig. 4, 51, 11, and through ground back to battery B. This causes the

switch 9 to step around to the sixth vertical row of bank contacts whereupon the cut-off relay L^3 (Fig. 1) is energized by current from battery B (Fig. 4) through the circuit elements 58, upper contacts of row 33 of the switch bank contacts, 27, 3, L^3 , 68 to ground and back to battery B. At the same time battery is supplied to the subscriber's line in series with the sleeve relay 42 over a path 10 which may be traced from battery B (upper part of Fig. 4) through upper members of row 30 of the switch bank contacts, circuit elements 7, 140, 89, 42, 2, 70, to subscriber's station and back by way of 69, 1, 38, 141, 8, 15 lower contacts of row 30 back to battery B. The seventh break in the line, effected by the subscriber's dial 63, effects a momentary deenergization of the sleeve relay 42 whose armature falling back produces a 20 momentary closure of the circuit of the stepping magnet 11 whose energizing circuit may now be traced from battery B (Fig. 4), through wiper 7 to wire 140, as before traced, and thence through off normal switch 101, the cam 102 now having moved 25 into a position to close the same, thence through circuit elements 103, 104, 105, 51, 11, and through ground back to battery B. Similarly upon the eighth break in the line 30 circuit, the switch 9 is stepped again, this time onto the eighth vertical row of contacts, which connects the input circuit of the subscriber's line tube 37 onto the program bus wires 68 through the eighth pair of contacts 35 in row 32 and switch wipers 25—26. The switch wipers 23—24 engaging the eighth pair of contacts, connect the battery B^3 , individual to the number 8 program, through conductors 74 and 76 through the windings 40 34 and 35 of the repeat coil 36 to the output or plate circuit of the subscriber's line tube 37, while the switch wipers 7 and 8 maintain the connection with the battery B through the multiple contacts of row 33 and 45 so supply current over the subscriber's line as before traced. Also, as in Fig. 2, the filament circuit of the subscriber's line tube 37 will be supplied with current from the filament battery A^3 individual to the number 8 program, the connections for this being the same as that of Fig. 2. Also, as in Fig. 2, the cut off relay, busy test and meter control circuit 3 is completed through 50 wiper contact 27. The circuit of the cut off relay may be traced from battery B (Fig. 4) through the circuit elements 58, upper member of the engaged contact in row 33, 27, 3, into Fig. 1, L^3 , 68, and back to battery B. The tone test is imposed upon this 55 circuit by the coupling of the tone test coil 87 with the coil 58 included in the test circuit in the usual manner well understood in the art, while the meter actuating source 91 and commutator 90 are connected with 60 this circuit through conductor 142. The cir-

cuit of the meter actuating current may thus be traced through the source 91, from the circuit elements 90, 142, 143, 27, 3, into Fig. 1, 95, meter M, to ground and back to the source 91.

In Fig. 5, is shown diagrammatically, a switch circuit which is a simplified form of the circuit arrangement of Fig. 4 in which the number of switch wipers are reduced to a minimum by delegating the control of certain circuits which are common to all the programs, to a cam actuated switch operable to maintain said circuits closed only during the engagement of the switch wipers with the program contacts. In this, as in the other switch arrangements previously described, the contact bank of the switch is provided with several vertical rows of blank contacts for example, five in number, not shown, for the purpose of permitting the switch to be stepped around several steps without effecting connection with any program transmitters. Parts of the present switching arrangement which are similar to and perform the same function as corresponding parts in the previously described switching arrangement, are similarly numbered. For example, the battery supply for the output circuit of the subscriber's line tube or relay 37 is furnished through wipers 23 and 24 and the top row of bank contacts, the connection between the input circuit of the subscriber's line relay tube 37 and the program source, is effected through wipers 25 and 26 and the second horizontal row of bank contacts, the filament current supply is furnished through wipers 26 and 28 and their associated contacts, and the metering circuit is connected through wiper 27 and its associated contact, with the metering actuating source. All of these circuits are to be connected with sources individual to a program and so their control is delegated to the wipers which change connection with each step of the switch. Thus, circuit connections which are not individual to a program such as the connections effected through the multiple line conductors 1—2, test conductor 3, and impulse conductor 4, are controlled through the cam operated switch 145. This switch is controlled by the cam 146 carried by the switch shaft 10 to maintain the contacts open when the switch is in its normal position or has moved into a position in which its wipers are on any of the blank contacts, and will maintain its contacts closed in any position of the switch in which the switch wipers are in engagement with a set of the program contacts. Another feature characteristic to the present switch arrangement is the position of the individual meter 1M individual to the switch circuit so as to meter only the use of the subscriber's line for broadcast reception. As with the other switching diagram, the pres-

ent diagram is to be read in connection with Fig. 1, the conductors 1, 2, 3, and 4 of Fig. 5 tying onto the conductors 1, 2, 3 and 4 of Fig. 1 respectively.

- 5 In the operation of this arrangement, the impulses sent over wire 4 from the subscriber's line relay in Fig. 1, pass directly to the stepping magnet 11 through conductor 146 until the switch has been stepped 70 around to the sixth row of contacts whereupon the contacts of switch 145 are closed, the sleeve relay 42 energized in series with the subscriber's line and the cut off relay in Fig. 1 energized to disconnect the line relay, 75 which now causes the further stepping of the switch to be controlled through the sleeve relay as a repeating relay responding to breaks in the subscriber's line circuit. The circuit of the cut off relay (Fig. 1) may 80 be traced from battery B (Fig. 5), supervisory lamp 147, conductor 148, contact of switch 145, conductor 3, into Fig. 1, cut off relay L³, conductor 68 to ground and back to battery B. The energization of the cut 85 off relay L³ causes the line relay L' to become deenergized and open the circuit through the impulse conductor 4 as before described in connection with Figs. 1 and 2. At the same time the cut off relay is deenergized to bring about the disconnection of the 90 circuit through conductor 4, the sleeve relay 42 is energized in series with the subscriber's line by a circuit which may be traced from battery B through the circuit elements 39, 42, 2, 70, over the subscriber's line and back by way of circuit elements 69, 1, 38, to battery B. Upon the next momentary break in the subscriber's line circuit the sleeve relay 42, being energized in series therewith, 95 is momentarily deprived of current which causes a momentary retraction of its armature, which in turn closes the circuit of the stepping magnet 11 which may be now traced from battery B through the circuit elements 104, 105, 146, 11, to ground and back to battery B. Thus, each momentary 100 break in the subscriber's line circuit causes the switch to make one step. When the switch comes to rest with its switch wipers 105 on the vertical row of contacts corresponding to the desired program, the sleeve relay 42 remains energized maintaining a shunt around the lamp 147 through resistance 149 thus extinguishing the signal light. This is 110 the operating position of the switch, and during the maintenance of this connection, assuming the switch wipers to be in contact with the vertical row of bank contacts associated with the number 7 program, the individual, broadcast service meter will be intermittently energized in a circuit which may be traced from the meter energizing source 91, through commutator 151, switch 152, upper member of the bottom pair of 115 contacts in the eighth row, switch wiper 27,

conductor 153, meter IM to ground and back to the source 91. It will be noted here that by movement of the switch arm 152 to its right hand contact the meter will be controlled through the commutator 150 instead of 152. As these commutators are arranged to close and open the circuit at different periodicity, the meter will be operated at a different rate thus making a different charge per hour for the service. For the purpose 75 of assigning different rates to different programs the switches 152 and 154 included in the meter circuits of the different programs, respectively, are arranged, as shown, with different contacts connected with the different commutators 150 and 151, respectively. Thus, with the meter control commutators 150 and 151 associated with different programs, the subscriber's service charges as recorded by his broadcast meter IM will vary 80 according to the particular program taken by him. To enable the operator or supervisor having charge of a number of switching devices like the present one, to listen in on the subscriber's line in the usual manner as in a telephone operator's cord circuit for the purpose of communicating with the subscriber, a listening key K' is provided arranged to connect a suitable listening set, not shown. The subscriber may apprise such 85 supervisor of his wish for some special service by making several successive momentary breaks in his line circuit much in excess of that required for the stepping of the switch to any of the sets of program contacts during which the supervisor noticing the apparent constant flickering of the supervisory lamp 147, will operate the listening key K' to ascertain the wants of the subscriber. To enable the supervisor to call the subscriber during the connection of his line through the switch mechanism, a special signaling key S' is provided which is arranged to connect the inductance coil 154 across the subscriber's line, which coil is inductively connected with the special tone signal circuit 100 500 and thus puts the signal on the line to be heard in the subscriber's loud speaker. To enable the subscriber to receive other broadcast items not on the programs to which his switch has access, the last vertical row of contacts in the switch have their program contacts such as 155 connected to a special program trunk 156 terminating in a jack 157 situated before what may be termed 105 a special program operator who has access to trunks leading to other stations providing different broadcast items, and who is also provided with means, such as telephone plugs forming the terminals of such trunks, for connection of any of said trunks to the special program contacts 155 through the jack 157, and short trunk 156. When the subscriber desires such special items he signals the supervisor in charge of the broad- 110 115 120 125 130

cast service by sending in the excessive number of breaks to signal the supervisor through actuation of the lamp 147 as before described, the extra number of breaks in the line circuit causing the switch to step around to the last vertical row of contacts and there come to rest, which disconnects the subscriber's line from all of the regular programs and connects it through the switch 10 wipers 25—26 and special programs contacts 155 to the trunk 156 terminating in the jack 157. The supervisor listening in through use of the key K' may now ascertain the wants of the subscriber and communicate 15 the same to the special program operator over a suitable order circuit not shown. The special program operator may then give the subscriber the program or item desired, by inserting the terminal plug of the appropriate trunk in the jack 157. This trunking arrangement for supplying the special programs from other stations will be clearly understood from an inspection of Figs. 6 and 7.

In Fig. 6 is diagrammed a portion of a 25 general system of broadcast distribution comprising a master station A, broadcast service station B, subscribers' central stations C, and subscribers' substations D, the relation of the stations A, B, and C being 30 the same as that described in my copending application Serial No. 746,357, filed October 28, 1924, except that the broadcast matter is transmitted from the B stations to the C stations as audio, or telephone currents over 35 wire trunk lines T^a, T^b, and T^c. The C stations, together with the subscribers' substations D are provided with means in the form of the circuits herein previously described in detail, for distributing the broadcast matter from the B stations to the subscribers' 40 stations D. The broadcast matter is originated or received from the other stations and put onto the program contacts of the subscriber's selector switches over the program 45 trunks T^a, T^b, and T^c by any known or other suitable form of apparatus symbolized at P^a, P^b, and P^c (Fig. 3), located at the B or service station.

In Fig. 7 is shown diagrammatically, the 50 special trunking system enabling a subscriber at a D station to extend his line beyond his associated central station either directly, or through other stations of the system to some particular station for the purpose of receiving the broadcast program there originated or there available through suitable relay apparatus, for example, station B². For this purpose, the special program operator at the C station is provided 55 with a link circuit LC capable of connecting a trunk terminal jack 160 with the subscriber's special jack 157 (the same as 157 of Fig. 5) through a detector and amplifier unit DA. The jack 160 forms the terminal 60 of a trunk 161 terminating in the "B" station B' in the output circuit of a line amplifier tube 137 whose input circuit terminates in a jack 162. Similarly, the station B' is provided with the circuit LB' arranged to connect the jack 162 with the jack 163 to an 65 amplifier unit IA, the jack 163 forming the terminal of a trunk 159 which terminates in the output circuit of a line tube 237 at the "A" station, the input circuit of which tube terminates in the jack 164. At the "A" station is provided an amplifying link circuit LA the same as that of station B' arranged to connect the jack 164 with a jack 165 forming the terminal of a trunk 158 terminating in a line tube 337, and jack 159 at station 70 B² in the same manner as that of the trunks 159 and 161. At the station B² is provided a link circuit LB² similar to those at stations A and B' and arranged to connect the jack 159 with the broadcast program apparatus 75 166 which may be a local source of broadcast matter or suitable relay device capable of relaying broadcast from some other station. Thus with the trunking system so described the subscriber at a D station may extend his 80 line to the broadcast transmitter 166 of the station B² over the trunking connection which may be traced from 160 through the trunking elements 159, 337, 158, 165, LA, 164, 237, 159, 163, LB', 162, 137, 161, 160, LC, 157, 37, to subscriber's station D. In the present illustration this broadcast matter is transmitted from the station B² over the trunks 158, 159, and 161 by carrier current, 85 which is detected and amplified in the detector amplifier unit DA at the C station and from thence transmitted to the subscriber's station at audio frequency or in the form of the original modulations, the amplifier units IA at the stations B², A, and B' being operable on the intermediate or carrier current frequency. In Figs. 6 and 7, the trunks 161, 159 and 158 are symbolical of a plurality of trunks which afford trunking distribution 90 out from any of the stations to several C stations directly or through other stations. It is also to be noted that the outgoing terminal of each trunk line is provided with a line tube similar to that of the subscriber's line tube which acts as an amplifier or relay so that throughout the several links, the line 95 tubes or relays will operate to effect gradual amplification throughout the distribution thus avoiding the losses and the necessity for currents of large magnitude incident to long distant distribution without the use of increments of power between the source and destination. It will be obvious that where 100 conditions are favorable, the amplifiers IA at the intermediate stations A, B', etc., may consist of but one step or may even be omitted or replaced by suitable coupling means, the line tubes or relays 137, 237, etc., being relied upon for effecting the necessary amplification.

The arrangement of circuits and apparatus for carrying out the idea of distribution with gradual amplification or increments of power at a broadcast distributing central is 5 diagrammatically shown in Fig. 8, where a source of audio signals is indicated at 167, the signals of which are distributed through a transformer 168 and a group of several amplifier tubes 169 in multiple to the input 10 side of a suitable coupling means such as the audio transformer 170, the output side of which distributes through several amplifier tubes 37 to as many trunks or line circuits 173. The line circuits 173 represent the subscriber's lines such as the subscriber's line 15 69-70 of Fig. 1, while the amplifier tubes 37 represent the individual line tubes or relays such as 37 of Figs. 2, 4, etc. It will thus be seen that with this arrangement the 20 amount of power in any of the intermediate circuits may be considerably less than the total amount of power distributed.

It is to be noted that the broadcast matter may if desired be put on the program contacts of the switch banks in the form of modulated carrier current, in which instance the subscriber's line tubes 37 would be preceded each by a detector tube or other detecting 25 means individual to the line.

30 In its broadest aspect this invention has to do with the distribution to telephone subscribers of radio programs or broadcast matter, through the usual distributive channels provided and employed in telephone exchanges, that is to say, switching means of 35 some sort, with necessary line units such as the line tubes herein described, for passing the radio matter, in whatever form received, to and through the subscribers' lines as audio 40 frequency waves. It is to be understood, however, that many variations may be made in the form and design of the switching mechanism in the line units through which the broadcast matter is conveyed to the subscribers. Thus, instead of the equipment 45 shown in Figs. 2 and 4 each line may have multiple jacks and the program busses may have multiple jacks, with pairs of plugs manipulated by operators to make the desired connections. Such an arrangement will 50 employ some signalling means between the subscriber and the operator. Another modification would be the provision of multiple jacks and line lamps on the radio board, one 55 for each line, such line jacks being constructed with pairs of terminals in the jack forced together when a plug is inserted so as to connect the line with the output side of its tube 37, through wires 40 and 41 of Fig. 2, 60 providing contacts on the relay 42 to close the grid circuit 25-26 to the program busses. If selection of program be desired, the switch 65 shown in Figs. 2 and 4 would still be employed, but would be actuated, both as to stepping and restoring by the relay 42 alone.

With such a line jack, only dummy plugs would be required having no cord conductors, all contacts being made in the jack. In closing the line terminals of the jack to the output terminals of the tube circuit, provision 70 is also made for closing the test and cut-off circuits to the test thimbles and the relay L³ of Fig. 1, through the wire 3. The operation of this arrangement would be very simple, the subscriber desiring radio merely opening and closing his circuit rapidly, so as to flash his signal lamps on both the telephone and the radio switchboards, both of these lamps being connected in parallel in the same fashion as the lamp L² in Fig. 1, controlled 75 by the same line relay contact 71. The lamps flash, and signal to both the telephone and the radio operators that radio is desired. The radio operator thereupon sticks a dummy plug, which expands the subscriber's line 80 to the wires 40 and 41 direct (see Fig. 2) and also closes the circuit 3 to the cut off relay L³ (see Fig. 1). The relay 42 in Fig. 2 then pulls up on line current, and gives the subscriber control of the switch magnets 85 11 and 15, so that he may step the switch around to pick out any program he pleases. In such case the switch can be made very simple, having just as many contacts as 90 there are program items to be selected at any one time, and arranging the latter so that as soon as the switch wiper has passed off the last program contact, it will immediately be prepared to step on to the first one again, so that by continuous rotation any item of 95 any program may be selected in any desired order.

The foregoing modifications still employ switches. It is further possible to eliminate the mechanical switching means, and use 100 what the radio engineer would term coupling coils, or the equivalent. In a prior copending application, Serial No. 691,823 I have illustrated and described capacity wave collectors for transfer of energy waves from 105 one circuit to another nearby circuit; and in the present case I may employ other such capacity coupling or electromagnetic coupling coils, which includes what is commonly known as a "loop" antenna. In this case it 110 is advisable to modify the line receiving means for the radio impulse, employing instead of the tube 37 and the circuits thereof as shown in Figs. 2 and 4, a complete 115 radio frequency receiving set with its output terminals connected to the line on its grid filament or input terminals terminating on a joint coupling coil, receiving waves from another coil or an antenna constituting the terminal of the program bus or busses typified in Figs. 2 and 4. A convenient arrangement of these line coils or loose couplers would be in a circular figure around the program antenna, and to save space the line terminals or coils may be arranged in cir- 120

cles one above the other, so as to form the general figure of a cylinder with the program coil or antenna in the axis of the cylinder. I do not present this as the best form to be employed, as modifications can be made, each of which has certain advantages. For example, if the lines are arranged with their terminal coils independent, a directional selection may be attained by merely turning the coils in a manner well understood in the art. Assuming that there be several program busses each carrying amplified superaudio frequency modulated waves, then by directional arrangement of the subscriber's line coil, waves can be received at will from any of these antennae. Another modification, with either a movable or immovable line terminal coil, is selection by tuning. Assuming the frequencies on the different program antennae to be different from each other, then the subscriber by tuning his line to the coupling coil at central, can select any one of the programs he desires. In principle, this arrangement involves the following: first, taking an ordinary radio receiving set away from the subscriber's station and putting it at the central office, connecting him to it through the wired line circuit from his station to central, but retaining the tuning elements, or variable capacity and inductance, one or both under the control of the subscriber (of course they may be at the subscriber's station for direct, or at the central station for remote control by current variations over his line). Then, having placed the receiving instrument at the central station and providing the subscriber with means for tuning it to the frequency he may desire to receive, and providing coupling means or sending and receiving aerials (in effect) at the central station, where a short gap only is required to be bridged by the radio waves, a single tube regenerative set or a two-tube set with one stage of audio amplification, or a two-tube set with crystal detector reflex will work with efficiency under such conditions, receiving over say a 50 foot gap on a relatively small loop. With such a loop wave collector, there is very little danger of objectionable radiation from the set.

The psychology of these modifications, especially those employing radio coupling at the central station between the program busses and the lines, is simply that other things being equal, the first cost as well as the cost of maintenance and operation of tubes does not exceed that of a well made selective switch of the manual type shown in Figs. 2 and 4, and the circuits are simplified. Moreover, the radio switchboard equipped with such apparatus is more nearly in line with radio practice, as distinguished from telephone practice. If the A or filament battery circuit of each tube be discon-

nected except when receiving radio (assuming the A batteries to be common) the plate filament circuit terminals of the line tubes such as 37 may be left permanently connected to line. The B battery, as well as the line, is protected by the space resistance in the plate circuit.

Referring particularly to Fig. 1, it will be observed that this represents the ordinary telephone exchange, of which there may be one or several in a given local area served by some broadcasting relay station or studio. The same radio broadcasting station may have its bus wires T^a , T^b , T^c extending into a number of exchanges through cable, and in practice this or some equivalent arrangement is a necessity, since it would be bad practice to needlessly duplicate receiving and relaying apparatus at every telephone exchange. Regarding the telephone exchange with its line wires and subscribers' stations as a complete wired entity, we may provide the necessary local bus wires, local receiving and relaying apparatus for radio, at the telephone exchange and then provide a central studio or relay station such as described hereinbefore, for all of the associated groups of telephone central stations. The local receiving stations need not then be either complicated or powerful, and they would all be within the scope and control of the central studio and relay station. From each such local equipment however to and through the subscribers' lines, all connections, supervision, control, testing, metering, and the like, would belong in the telephone administration typified by the diagram in Fig. 1. Furthermore, according to this very necessary arrangement, the maintenance and supervision of all wires and operation from the telephone exchange to and including the subscriber's line, is for the telephone administration and particularly the wire chief and his assistants. Where there are several exchanges in the same area, all served by the same radio relay station and studio, there would be one wire chief for the area, with assistants at the different branch exchanges. It will then be understood that while the central studio from its own test boards would have access by wired trunk lines to each telephone exchange, and the receiving and relaying apparatus therein, this would be the limit for the studio, which would not have access to the subscribers' lines for any purposes except ordinary connection as between one subscriber and another. Moreover, all that has been said about the general practice involved and modifications in the embodiment herein described, is to be understood as applying to both manual and automatic switching apparatus in either the telephone administration or the radio administration side of the system, or both. I have chosen to illustrate herein as in prior applications co-

pending herewith, standard manual Western Electric apparatus. The reason for this is that the circuits involved therein are standard in themselves, and when stripped of limitations of form, are embodied without substantial change in either manual or automatic apparatus.

I believe all the modifications and all of the facts described herein by themselves and 10 in combination, when employed in the manner described, are novel and original with me, and I shall claim the same accordingly.

What I claim is:

1. In a system of broadcast distribution, a 15 broadcast service station having wire broadcast transmitting means situated thereat, a telephone central station with subscribers' stations and wire lines interconnecting them, a wire bus line connecting the transmitting 20 means at the broadcast service station with the central station, telephone relay means at the central station individual to each subscriber's line and means at the central station for connecting one or more subscribers' 25 lines each through its associated telephone relay means to the bus line leading from the service station, together with metering means controlled in the connection of a subscriber's telephone relay means.

2. In a system of broadcast distribution, a broadcast service station having wire broadcast transmitting means situated thereat, a telephone central station with subscribers' stations and wire lines interconnecting them, 30 a wire bus line connecting the transmitting means at the broadcast service station with the central station, telephone relay means at the central station individual to each subscriber's line and means at the central station 35 for connecting one or more subscribers' lines each through its associated telephone relay means to the bus line leading from the service station, together with means for recording the time use of said connection of a subscriber's line through its associated telephone relay means to the line leading from the service station.

3. In a system of broadcast distribution, a 40 station, a telephone central station with subscriber's stations and lines interconnecting

them, means for transmitting broadcast matter from said first mentioned station through the central station to the subscribers in common and means at the central station for recording the time use of the broadcast service to the subscribers. 55

4. In a system of broadcast distribution, a broadcast service station, a telephone central station with subscribers' stations and lines interconnecting them, program trunks between the service station and the central station, means at the broadcast station for transmitting different programs of broadcast matter over said program trunks to the central station, a telephone relay at the central station associated with each subscriber's line, and means controlled from any subscriber's station for selectively connecting its station with one of the program trunks through the said relay independently of the connection or non-connection of any other subscriber's station therewith, together with means associated with the receiving subscriber's equipment for differentially metering the time of transmission of the different 75 programs to that subscriber.

5. In a system of broadcast distribution, a broadcast service station, a telephone central station with subscribers' substations and line circuits interconnecting the same, a vacuum tube relay for each line at the central station, broadcast transmitting relay apparatus at the service station, a broadcast trunk line connecting the broadcast transmitting apparatus with the central station, 80 means at the central station whereby the input sides of said line tubes are connected to the broadcast trunk, and the output side of each line tube is connected to its own line, means at each subscriber's station to control 85 the connection of his own line tube at central and to disconnect the same when not receiving, and line service metering means controlled in said connection and disconnection, said metering means being located at 90 the central station and individual to the lines.

In testimony whereof I hereunto affix my signature.

EDWARD E. CLEMENT.
